APPENDIX

UNITED STATES PATENT OFFICE.

CHARLES B. HEATH, OF STOCKTON, CALIFORNIA, ASSIGNOR OF ONE-HALF TO G. W. QUIGLEY, OF STOCKTON, CALIFORNIA.

KITCHEN-CABINET.

1,208,153.

Specification of Letters Patent. Patented Dec. 12, 1916.

Application filed April 28, 1914. Serial No. 834,936.

To all whom it may concern:

Be it known that I, CHARLES B. HEATH, a citizen of the United States, residing at Stockton, in the county of San Joaquin and State of California, have invented new and useful Improvements in Kitchen-Cabinets, of which the following is a specification.

My invention relates to an apparatus in the form of a kitchen cabinet, in which the 10 various parts necessary for the operation of such a cabinet are so supported and correlated that they form a foldable and expandable device capable of being opened and expanded, or closed and stored out of sight 15 at pleasure.

My invention consists in the combination and arrangement of parts and in details of construction which will be more fully explained by reference to the accompanying 20 drawings, in which—

Figure 1 is a front view of the cabinet; Fig. 2 is a vertical section taken on line 2—2, Fig. 1; Fig. 3 is a section taken on line 3—3, Fig. 2; Fig. 4 is a view with the door 25 opened, showing the interior of the cabinet with the stove, sink and water supply; Fig. 5 is a sectional view taken on line 5—5 of Fig. 4; Fig. 6 is a horizontal section taken through the upper portion of the cabinet 30 and showing the parts in full extended position; Fig. 7 is a fragmentary view partly broken away, showing the table attached to the rear of the panel door and its supporting legs; Fig. 8 is a sectional view taken on 35 line 8—8 of Fig. 4, showing the arrangement of the gas stove attachment; Fig. 9 is a section taken on the line 9—9 of Fig. 2 showing the parts in closed position; and Fig. 10 is a section taken on the line 10—10 40 of Fig. 2.

In the construction of apartment houses and rooms adapted for residential purposes, it is often necessary to combine a great number of conveniences in a very limited space, 45 on account of the expense of the necessary rooms, and to arrange them in an orderly fashion. For this reason I have designed a cabinet, with the various conveniences and necessities of a kitchen and dining room, so 50 disposed and supported, with relation to each other, that they may be conveniently folded and inclosed in a small, inconspicu-

ous space, when not in use, and may, when in use be opened out to present the various articles of domestic furniture in convenient 55 relation with each other.

In carrying out my invention, I have designed a closet or cabinet A having a suitable or convenient number of horizontal shelves, as at B, forming intermediate chambers which serve partly to contain such articles as may be necessary and which are partly so arranged as to form pockets into which certain portions of the apparatus may be folded when closed. This cabinet is provided with a door 2, suitably hinged, as at 60 2^a, so that it may be opened or closed at will. The various portions of the apparatus are carried partly within the cabinet and partly upon the door. Their disposition is such 65 that parts of the apparatus are conveniently housed, or extended without interfering with each other.

In the lower portion of the cabinet I have shown a structure including a sink 3, a 75 slideable molding or drain-board 4, with a connected slideable drawer 4^a beneath, and a detachable pan 5 beneath the sink for the purpose of receiving any water therefrom which may be afterward easily disposed of. This 80 portion of the device is mounted upon legs 6 which may be provided with casters and which allow this portion to be drawn out for use, or closed into the cabinet when not in use. 85

The sink 3 is secured to and beneath the slideable drain board 4, so as to move therewith. The legs 6 are in rigid connection with the drain board 4 and may be connected thereto in any suitable manner, for instance 90 as shown in Fig. 4, one leg is rigidly secured to the sink 3, and the other to the drain board 4. As shown in Figs. 2 and 5, the drain board has an opening through which sink 3 is accessible. Above this sink one of 95 the shelves B is so disposed as to overlie a gas stove 7. This stove is mounted upon the hinged door 2 in such a way as to close into the space between the shelves when the door is closed. Surrounding the stove is a 100 shelf 8, hinged at one end so as to be folded up against the door, when not in use, and having a portion cut away so as to fit over the outline of the stove when it is brought

down into a horizontal position, so as to be supported horizontally by engagement with the stove and thus provide for the support of dishes, cooking utensils, etc., which are to be used about the stove. The shelf, while in its folded position, is so disposed that it does not interfere with the closing of the door.

- A warming shelf may be disposed above
- 10 the stove, as at 9, and above this is a hood, so disposed as to carry off the odors arising from the cooking. This hood is shown at 10 and is adapted to rotate about an axis and pins, as at 11, so that it may be extended 15 outwardly, when in use, thus insuring the collecting of rising vapors. The sides, ends and any suitable portion of the apparatus may be provided with screens, as at 11^a, to ventilate the cabinet.
- 20 In order to provide a convenient and available water supply, permanent water and gas pipes may be brought into the cabinet, as shown at 12, and flexible, jointed connections, as at 13, allow the gas to be 25 carried to those portions upon the door so that they will not interfere with the opening and closing thereof.

The door 2 has its lower panel 20 hinged vertically thereto at 21 so that the panel can 30 be moved to the out position shown in Fig. 6 so as to lie in the same plane with the door. A table 14 is hinged at 22 to the panel 20 so that the table may be moved to horizontal position and when in such position is supported by legs 15 which are hinged at 15' to the table 14 at the free lower or outer side thereof so as to fold against the table 14 and into the offset 20^a of panel 20 as shown in Fig. 2. The door 2 has an offset lower portion 2^b in which the table 14 folds, while the panel 20 in turn has an offset 20^a in which the legs 15, 15' of table 14 fold. A shelf 30 is attached by brackets 31 to the offset lower portion 2^b of door 2 and serves to hold utensils or other articles.

Having thus described my invention, what

I claim and desire to secure by Letters Patent is—

1. In a kitchen cabinet, a cabinet proper and a door vertically hinged thereto, a panel 50 for the lower portion of the door vertically hinged to the latter so that the panel may be swung outwardly to lie in the same plane with the door, said panel having its lower part offset, a table horizontally hinged to the panel and movable downwardly to engage the inner face of the panel, and legs hinged to the table at the free side thereof, said legs being movable to engage the under face of the table and when so engaged being 60 disposed in the offset of the panel.

2. In a kitchen cabinet, a cabinet proper, a door vertically hinged to the cabinet proper, a member vertically hinged to the outer side edge of the door so that the member 65 may be swung outwardly to lie in the same plane with the door and may be folded to lie substantially parallel to the door, a foldable table horizontally hinged to the member and when folded being movable to 70 lie substantially parallel to the door, and foldable means to horizontally support the table and when folded lying substantially parallel to the door.

3. In a kitchen cabinet, a cabinet proper, a door vertically hinged to the cabinet and having a lower offset extending inwardly of the cabinet, a panel vertically hinged to the door, said panel having a lower offset extending outwardly of the cabinet, and a 75 table horizontally hinged to the panel and foldable into the door offset, and foldable legs for the table foldable into the panel offset.

In testimony whereof I have hereunto set 80 my hand in the presence of two subscribing witnesses.

CHARLES B. HEATH.
